LOCKING COTTER-PIN.

1,057,218.

Specification of Letters Patent. Patented Mar. 25, 1913.

Application filed March 4, 1912. Serial No. 681,344.

To all whom it may concern:

Be it known that I, ANDREW C. CAMPBELL, a citizen of the United States, residing at Waterbury, in the county of New Haven and 5 State of Connecticut, have invented a new and useful Improvement in Locking Cotter-Pins, of which the following is a specification.

This invention relates to that class of pins 10 which are designed to be thrust through openings for the purpose of preventing the removal of the parts through which they are passed, or pieces located upon the parts through which the pins are put.

15 The object of the invention is to provide a simple and cheap cotter-pin which is so devised that after being thrust through a hole it can be easily manipulated so as to securely lock itself in place. This object is attained 20 by doubling a length of the commonly used wire upon itself so as to form an offset eye at one end and have one limb longer than the other, with the tip of the longer limb bent at an angle across the tip of the shorter, 25 in such manner that after the pin is thrust through the hole it is to occupy, a bar or tool blade can be put through the eye and twisted so as to draw back the long limb and cause 30 the bent tip to spread the ends of the limbs to a size that is greater than the diameter of the hole occupied by the pin.

Figure 1 of the accompanying drawings shows a cotter-pin which embodies the invention in its original shape thrust through 35 a perforation in a piece of metal. Fig. 2 is a view of the same after the pin has been manipulated by a bar so that the long limb is drawn back and its bent tip has caused an expansion of the ends for the purpose of 40 locking the pin in place.

These pins are desirably manufactured on an automatic forming machine of the necessary lengths cut from a coil of half round wire of the desired diameter. The wire is 45 bent to form an eye 1 at one end and bring the flat surfaces together and provide the short limb 2 and the long limb 3. The eye is offset on the side of the short limb. The tip 4 of the long limb is bent at an angle 50 across the tip 5 of the short limb. When the wire is cut for the purpose of severing a length for making the pin, the end which is to form the tip of the long limb is de-

sirably shaped so that when this tip is bent across the tip of the short limb, the transverse section of the end will be practically a circle of the same size as the two limbs, which is usually a little less than the diameter of the hole through which the pin is to be thrust. These pins can be made as rapidly and cheaply as the common cotter-pin, which has limbs of equal length and the tips of which have to be separated and spread apart by a suitable instrument after the pin has been driven in place. After one of 65 these improved pins has been thrust into a hole for fastening the part in which it is placed, or for holding a piece on that part, a bar or tool blade 6 is passed through the eye and then twisted. As the eye is offset 70 on the side of the short limb, the bar is twisted so as to hold the short limb and pull back the long limb and as the bent or offset tip of the long limb is drawn back past the tip of the short limb, the ends of the pin are 75 wedged apart so that they occupy a space that is greater than the hole through which the pin was driven, as shown in Fig. 2. In this simple manner the pin is locked in position and cannot be removed until the 80 manipulation is reversed, either by driving forward the long limb or driving back the short limb sufficiently to allow the ends to spring together.

The invention claimed is:

1. A cotter-pin made of a piece of wire bent to shape and having two integral limbs joined by an oblong eye at one end, said limbs being of unequal length and having the end of one bent transversely into the 90 path of the other, and said eye having a portion offset on the side of the limb having the straight end whereby the bent limb can be drawn back with relation to the straight limb and the ends of the limbs spread by 95 inserting into the eye and turning therein an oblong implement.

2. A cotter-pin made of a piece of wire bent so as to form an offset eye at one end and have two limbs of unequal length, the 100 said eye being offset on the side of the short limb and the tip of the long limb being bent at an angle across the tip of the short limb.

3. A cotter-pin made of a piece of wire bent so as to form an oblong eye at one 105 end and provide two limbs of unequal

length, one side of the eye being straight with relation to the long limb and the other side of the eye being offset with relation to the short limb, the tip of the long limb being bent across the tip of the short limb, whereby said eye may be opened by turning an oblong implement therein, and the long

limb drawn back with relation to the short limb so that the tips will engage and cause a spread of the free ends of the limbs.

ANDREW C. CAMPBELL.
